(57) **CLAIM**

The ornamental design for a training equipment, as shown and described.

DESCRIPTION

FIG. 1 is a perspective view of a training equipment showing my new design.

FIG. 2 is a front view thereof, a rear view being a mirror image of the front view;

FIG. 3 is a right side view thereof, a left side view being a mirror image of the right side view;

FIG. 4 is a top view thereof; and,

FIG. 5 is a bottom view thereof.

The broken lines depict portions of the training equipment and forms no part of the claimed design.

1 Claim, 5 Drawing Sheets
